UNITED STATES PATENT OFFICE

97,120

DESIGN FOR A DRESS

Madeleine Croizat, New York, N. Y.

Application September 5, 1935, Serial No. 58,440

Term of patent 3½ years

To all whom it may concern:

Be it known that I, Madeleine Croizat, a citizen of the United States of America, residing in Manhattan, county of New York, and State of New York, have invented a new, original, and ornamental Design for a Dress, of which the following is a specification, reference being had to the accompanying drawing, forming part thereof, wherein,

The triangular structures attached to the front side portion of the collar, represent inner lapels.

I claim:

The ornamental design for a dress, substantially as shown and described.

MADELEINE CROIZAT.
